A. J. LECOUTRE.

CORSET.

APPLICATION FILED JAN. 12, 1918.

1,304,891.

Patented May 27, 1919.

Inventor
Auguste J. Lecoutre

By John S. Dewey
Attorney.

UNITED STATES PATENT OFFICE.

AUGUSTE JEAN LECOUTRE, OF WORCESTER, MASSACHUSETTS, ASSIGNOR TO ROYAL WORCESTER CORSET CO., OF WORCESTER, MASSACHUSETTS, A CORPORATION OF MASSACHUSETTS.

CORSET.

1,304,891.

Specification of Letters Patent. Patented May 27, 1919.

Application filed January 12, 1918. Serial No. 211,480.

To all whom it may concern:

Be it known that I, AUGUSTE J. LECOUTRE, a citizen of the United States, residing at Worcester, in the county of Worcester and 5 State of Massachusetts, have invented certain new and useful Improvements in Corsets, of which the following is a specification.

My invention relates to improvements in 10 corsets, particularly to that class of corsets which have a shield or tongue back of the lacing, to cover the space or opening between the two sections laced together.

The object of my invention is to provide 15 an improved shield or tongue for corsets of the class above referred to.

My invention consists in certain novel features of construction of my improved shield or tongue, combined with the corset, as will 20 be hereinafter described.

In my improvements, I provide a shield or tongue made separate from and independent 25 of the corset. The shield or tongue is preferably provided with one or more transverse bones or stiffeners, and one or more bones or stiffeners extending in the direction of the length of the shield. The upper end of the shield or tongue is provided with attaching 30 tapes, which extend out from each side edge of the shield or tongue, and act to secure the shield or tongue at its upper end to the two sides or sections of the corset. The shield or tongue is also provided at its lower end with two attaching tapes which extend out 35 from each side edge of the shield or tongue, and act to secure the shield or tongue at its lower end to the two sides or sections of the corset. The shield or tongue, except for its attachment by the tapes at its upper end, 40 and at its lower end, is entirely free from the corset.

Referring to the drawing:—

Figure 1 shows a detached portion of two 45 front sections of a front laced corset, and my shield or tongue combined therewith.

Fig. 2 is a section, on line 2, 2, Fig. 1, looking in the direction of arrow *a*, same figure, with the lacing left out.

Fig. 3 corresponds to Fig. 2, but shows the 50 two sections of the corset drawn together, with the shield or tongue extending back of the lacing; the lacing is shown in this figure.

Fig. 4 shows the shield or tongue detached.

55 In the accompanying drawing, 1 is a de-

tached portion of a front section of a front laced corset; 2 is the second front section of the corset, having a steel with fastening clasps 3 thereon; 4 is a floating edge, so termed, having the studs 5 thereon, to be detachably connected with the clasps 3 in the usual way. 6 is the usual lacing, which is passed through eyelets 1', and 4' in the section 1, and the floating edge 4, respectively.

All of the above parts may be of the usual and well known construction.

I will now describe my improvements in shield or tongue.

The shield or tongue 7, shown detached in 70 Fig. 4, is preferably made of one thickness of textile fabric and in one piece, and provided with binding or edging 7' on each side edge, and with binding or edging 7" on the top edge and on the bottom edge. The binding or edging 7" extends out beyond the side edges, at the upper end, and at the lower end of the shield or tongue, to form 75 attaching tapes 7'''.

The shield or tongue 7 has in this instance 80 three transverse bones or stiffeners 7", which extend in the direction of the width of the shield or tongue 7, and are secured thereto in any suitable manner. There are also in this instance two vertically extending bones 85 7", which extend in the direction of the length of the shield or tongue 7, and are secured thereto in any suitable manner.

The shield or tongue 7 extends in a vertical direction on the inside of the corset, 90 back of the lacing and of the opening between the edges of the section 1, and the floating edge 4, and preferably extends for about two-thirds, or three-quarters the length of the corset. One of the tapes, 7''' 95 at the upper end of the shield 7 is attached to the section 1, and the other tape 7''' at the upper end of the shield 7, is attached to the floating edge 4. One of the tapes as 7''' at the lower end of the shield 7 is attached to the section 1, and the other tape 7''' at the lower end of the shield 7, is attached to the floating edge 4. The shield or tongue 7 is entirely free from the corset, except at its upper end, and at its lower end, 100 but is held in proper position, relative to the corset, by the attaching tapes at its upper end, and at its lower end.

When the lacing 6 is drawn up, to bring 110 the section 1 and the floating edge 4 toward

each other, the flexible attaching tapes 7''' are drawn toward each other, at the upper end and at the lower end of the shield 7, leaving the shield in a flat and smooth position, back of the drawn up lacing, as shown in Fig. 3.

The shield 7, by reason of its attachment only at its upper, and lower edge, by the flexible attaching tapes 7''', may adjust 10 itself laterally, and also vertically to a limited extent, back of the laced parts, in lacing up said parts on the wearer.

I have shown my improvements in shield or tongue for corsets, combined with the 15 front section of a front laced corset, but my improvements may be equally well combined with the rear section of a back laced corset, if desired.

It will be understood that the details of 20 construction of my improvements may be varied if desired.

Having thus described my invention, what I claim as new and desire to secure by Letters Patent is:

25 1. In a corset, the combination with two parts laced together, of a shield adapted to extend back of said two parts, and having on its upper edge a binding which extends out beyond the side edges of the shield, and

has each extended end permanently attached 30 to said two parts, and having on its lower edge a binding which extends out beyond the side edges of the shield, and has each extended end permanently attached to said two parts, to leave the shield, intermediate 35 its upper and lower end, unattached to the corset, and free to adjust itself relatively to the two laced parts of the corset.

2. In a corset, the combination with two parts laced together, of a shield adapted to 40 extend back of said two parts, and having on its upper edge a binding which extends out beyond the side edges of the shield, and has each extended end permanently attached to said two parts, and having on its lower edge a binding which extends out beyond the side edges of the shield and has each extended end permanently attached to said two parts to leave the shield, intermediate 45 its upper and lower end, unattached to the corset and free to adjust itself relatively to the two laced parts of the corset, and said shield provided with transverse stiffeners, and with vertically extending stiffeners.

AUGUSTE JEAN LECOUTRE.
